(57) **CLAIM**

I claim the ornamental design for a paving slab, as shown and described.

DESCRIPTION

FIG. 1 is a perspective view of a paving slab according to a first embodiment of the present design;

FIG. 2 is a top view thereof;

FIG. 3 is a left view thereof;

FIG. 4 is a front view thereof;

FIG. 5 is a right side view thereof;

FIG. 6 is a rear side view thereof;

FIG. 7 is a top view thereof with other paving units shown in broken lines;

FIG. 8 is a perspective view of a paving slab according to a second embodiment of the present design;

FIG. 9 is a top view thereof;

FIG. 10 is a left view thereof;

FIG. 11 is a front view thereof;

FIG. 12 is a right side view thereof;

FIG. 13 is a rear side view thereof; and,

FIG. 14 is a top view thereof with other paving units shown in broken lines.

The broken lines depict environmental structure and portions of the paving slab that form no part of the claimed design.
